US00D936860S

(12) **United States Design Patent** (10) Patent No.: **US D936,860 S**
Styrc et al. (45) Date of Patent: **** Nov. 23, 2021**

(54) **CONNECTOR FOR A MODULAR STRUCTURE**

(71) Applicant: **2724889 ONTARIO INC.**, Oakville (CA)

(72) Inventors: **Jacek Styrc**, Oakville (CA); **Sebastian Lysiak**, Bielsko-Biala (PL)

(73) Assignee: **2724889 ONTARIO INC.**, Oakville (CA)

(**) Term: **15 Years**

(21) Appl. No.: **29/723,173**

(22) Filed: **Feb. 5, 2020**

(56)

CLAIM

The ornamental design for a connector for a modular structure, substantially as shown and described.

DESCRIPTION

FIG. 1 is a perspective view of the connector for a modular structure;
 FIG. 2 is a rear elevation of the connector for a modular structure of FIG. 1;
 FIG. 3 is a front elevation of the connector for a modular structure of FIG. 1;
 FIG. 4 is a plan view of the connector for a modular structure of FIG. 1;
 FIG. 5 is a bottom view of the connector for a modular structure of FIG. 1;
 FIG. 6 is a side elevation of the connector for a modular structure of FIG. 1; and

FIG. 7 is a side elevation from the opposite side to FIG. 6 of the connector for a modular structure of FIG. 1;
FIG. 8 is a perspective view of a variant of the connector for a modular structure;
FIG. 9 is a rear elevation of the connector for a modular structure of FIG. 8;
FIG. 10 is a front elevation of the connector for a modular structure of FIG. 8;
FIG. 11 is a plan view of the connector for a modular structure of FIG. 8;
FIG. 12 is a bottom view of the connector for a modular structure of FIG. 8;
FIG. 13 is a side elevation of the connector for a modular structure of FIG. 8; and,
FIG. 14 is a side elevation from the opposite side to FIG. 13 of the connector for a modular structure of FIG. 8.
